UNITED STATES PATENT OFFICE.

WILLIAM F. TILL, OF BROOKLYN, NEW YORK.

METHOD OF MAKING TOILET SEATS.

Application filed March 20, 1928. Serial No. 263,143.

This invention is a method of making toilet seats and more particularly from wooden sections permanently screwed together in such manner that the means whereby they are retained in an assembled relation is fully concealed.

Seats of this general character are well-known and numerous methods have heretofore been employed in their construction. 10 The primary consideration, however, in the manufacture of this type of seat is to so assemble the sections of which the seat is composed as to make absolutely closed joints which will not open even after long periods of use. It has been suggested heretofore to assemble seat sections by the application of pressure to the exterior edges of the outer sections, in order to force the tie members into the respective sections. Hydraulic presses 20 are generally employed for this purpose and considerable pressure is used. It is found in practice, however, that when pressure is applied, as stated, the natural resiliency of the wood acts as a cushion. In effect it tends to take up the pressure and spring back when the pressure is relieved so that it is very difficult to get the joints absolutely tight initially and to maintain them tight thereafter.

30 With the foregoing considerations in mind I have conceived the present method of this invention which, instead of utilizing pressure directed upon the parts remote from the anchoring means, tension is utilized 35 to draw such sections together. This tension, moreover, is applied to the respective sections in such manner and in such localities as to eliminate the disadvantages to which I have referred and to insure permanently tight joints.

40 Thus, in practicing the present invention, I apply tension to the respective sections adjacent to the edges which are to be brought into abutting relation and utilize this tension, as applied to the respective sections, to force tie members simultaneously into the respective sections. In other words, the sections are drawn together in contradistinction to being forced together by externally applied pressure. In one of the practical modes of practicing the invention, in connection, for example, with a two-piece seat the edges of the respective sections which are to be brought into abutting relation are 50 squared true so as to make a proper joint

when brought together. The sections are then provided with lined holes adapted to receive tie members. These tie members are in the form of double-ended screws, the central portion of each of which is left unthreaded, while the opposite ends have right and left hand threads or convolutions. The opposite ends of the sections are notched out contiguous to the fitted edges and from the bases of these notches lined holes are bored 60 to receive tension members. The holes bored for these latter members are slightly smaller than said members while the holes bored for the tie members are slightly smaller than diameters of said members, 65 the purpose being to permit introduction of the respective members without splitting the wood and yet permit the threads to get a good grip.

70 By the employment of the tension members the sections may be drawn together for the purpose of forcing the tie members simultaneously into the holes of both sections in order to affect a tie joint and anchor the parts together.

75 Features of the invention other than those specified will be apparent from the herein-after detailed description and claims, when read in conjunction with the accompanying drawings.

80 In the accompanying drawings I have shown the preferred manner of practicing the present invention but the showing there made is for the purpose of illustration only and does not define the limits of the invention.

85 Figures 1-6, inclusive, show progressive steps in the method of making toilet seats in accordance with this invention.

Figure 7 illustrates a tension member used 90 in carrying out the method.

Figure 8 shows one of the tie members.

Figure 9 illustrates the method of this invention as practiced in the making of a 95 four-piece seat.

100 In making a two-piece seat, in accordance with the present invention, I start with two pieces of wood which are first cut, as shown in Figure 1, to form two sections, 1 and 2, which are identical with one another. The edges, 3 and 4, of these sections are the jointed edges which are adapted to be brought together to form the joint. Adjacent to these edges, at opposite ends of each section, notches are cut out, as shown at 5, 110

- and from the base of these notches holes, 6, 7, 8 and 9, are bored so that the holes, 6, and 7, will be in alinement and the holes, 8 and 9, will be similarly positioned. Holes, 10, 11, 12 and 13 are also bored in respective sections to project inwardly from the edges, as shown, and in such position that the holes, 10 and 11, will be in alinement and that the holes, 12 and 13, will be similarly disposed.
- 5 10 The holes, 10, 11, 12 and 13 are intended for the reception of tie members, one of which is shown in detail in Figure 8. Each tie member is provided with a central portion, 14, while beyond the opposite ends of the portion, 14, the tie member is provided with right and left hand threads, 15 and 16, respectively. I wish to call particular attention to the fact that the threads, 15 and 16, are of an unusually long pitch, e. g., triple 20 thread, so as to screw into wood with a long lead and with expedition.
- The holes, 6, 7, 8, and 9 are adapted to cooperate with tension members, one of which is shown in Figure 7, each tension member 25 has a central polygonal portion 17, and opposite end portions, 18 and 19, are provided with right and left hand threads, respectively. The threads of the parts, 18 and 19, are similar to those employed on lag-screws 30 and their pitch is materially less than the threads of the tie members. The purpose of this arrangement is to provide for the application of relatively great power through operation of the tension members in order to 35 cause the tie members to enter the holes, 10-13. The long lead of the tie members permits them to be anchored easily while the short lead of the tension members allows of the application of relatively great power.
- 40 In assembling the parts they are first brought into the position shown in Figure 1 with the opposite ends of the tie members entered into the holes, 10-13. The tie members are then rotated, either manually or 45 by the use of any appropriate machinery, to screw them into the respective sections. This operation will cause sections to be drawn together and is continued until they are in about the relation, shown in Figure 2. The 50 tie members are thereupon "backed off" or unscrewed slightly to approximate the position of the parts, shown in Figure 3, and the tension members are then brought into the positions shown in this figure. From 55 this point on the tie members are not directly operated upon but in contra-distinction the tension members are operated by suitable machinery or manually to draw the sections together. As the sections are drawn 60 together the spiral or threaded portions of the tie members cut threads in the holes, 10-13, and are rotated to screw into the respective sections by virtue of the tension to which said sections are subjected.
- 65 Inasmuch as the tie members have been

retracted slightly before introduction of the tension members, the tension members will operate easily at the start of the next operation which consists in rotating the tension members to draw the seat sections together so 70 that by the time the tie members have to start again to cut their own thread the tension members have cut sufficiently into the sections so as not to pull out. By proceeding with this operation the sections are drawn 75 tightly together, as shown in Figure 4, thereafter the end portions of the respective sections are cut away, as shown by the dotted lines, 20, leaving the finished blank, shown in Figure 5. This blank is then acted upon 80 by suitable woodworking machinery to shape it into the finished form, shown in Figure 6.

In Figure 9, I have illustrated the manner in which the method of this invention is utilized in the method of a four-piece seat. 85 In this figure the sections, 1^A and 2^A, correspond to the sections, 1 and 2, but intermediate sections, 21 and 22, are added. These intermediate sections are bored to provide holes for the tie members but these holes are 90 sufficiently large to permit such tie members to readily slip therethrough. The parts are assembled in the same manner as previously described although the tie members, shown in Figure 9, have a longer, unthreaded, central section corresponding to the section, 14, and shorter threaded end sections so that suitable tools may be applied to these tie 95 members in order to carry out the method as hereinbefore defined.

100 It will, of course, be understood that the joints produced, as stated, may be doweled, tongued and grooved, or otherwise suitably formed in order to produce a positive lock at the joint so that there may be no displacement of the sections relative to one another in a direction perpendicular to the face of the seat. As this practice is, however, well-known in the art I have not considered it necessary to illustrate these adjuncts.

105 It will further be understood that the parts cut away from the ends of the respective sections, as along the lines 20, are separated from the tension members in order to permit of further use of said members in 110 connection with other seats.

I wish to call particular attention to the 115 fact that the tension which serves to draw the sections together is applied from the edges which are to be joined. It is a common practice to use fairly straight-grained wood in the manufacture of articles of the character under consideration and it, therefore, follows that the tension devices act through substantially the same grain as receive the tie members. There is, therefore, little tendency of compression on this grain and the power is localized in such manner as to produce the most efficient results.

120 125 130 I have not shown or described any par-

ticular mechanism, wrenches, or the like, for manipulating either the tie members or the tension members. In practice, these may be operated upon either manually by the employment of wrenches or other implements, or they may be operated by any suitable power mechanism or machinery.

The parts are placed under no such compression as would cause them to expand in a manner to open the joints and experience has shown that the joints will remain tight indefinitely.

The foregoing detailed description sets forth the invention in its preferred practical application but the invention is to be understood to be fully commensurate with the appended claims.

Having thus described my invention what I claim as new and desire to secure by Letters Patent is:

1. The herein described method of making a toilet seat which consists in bringing the sections of the seat into spaced-apart juxtaposition with right and left hand threaded tie members projected into aligned holes in the respective sections, and thereafter drawing said sections together by applying tension between them for the purpose of fully entering the tie members into the holes of the respective sections and bringing the contiguous edges of such sections into abutting relation.

2. The herein described method of making a toilet seat which consists in bringing the sections of the seat into spaced-apart juxtaposition with right and left hand threaded tie members projected into aligned holes in the respective sections, and thereafter applying tension between the contiguous edges of said sections to draw said sections toward one another for the purpose of forcing the tie members to simultaneously rotate and enter said sections until the contiguous edges of the sections are in tight, abutting relation.

3. The herein described method of making a toilet seat which consists in bringing the sections of the seat into spaced-apart juxtaposition with right and left hand threaded tie members projected into aligned holes in

the respective sections, thereafter bringing additional right and left hand screw members into holes in the contiguous edges of said sections and through tightening said additional screw members to draw the sections together whereby the tie members are caused to rotate and simultaneously enter the respective sections until the contiguous edges of said sections are in tight and abutting relation.

4. The herein described method of making a toilet seat which consists in bringing the sections of the seat into spaced-apart juxtaposed relation with tie members, having long pitch, right and left screw threads on their opposite ends, partially projecting into aligned holes in respective sections through causing right and left hand tension screws, of less pitch, to be screwed simultaneously into both sections for the purpose of drawing such sections together with greater power than resistance offered by the tie members whereby the sections are caused to move toward one another and screw the tie members into the respective sections until the contiguous edges of said sections are in abutting relation.

5. The herein described method of making a toilet seat which consists in bringing the sections of the seat into spaced-apart juxtaposed relation with tie members, having long pitch, right and left screw threads on their opposite ends, partially projecting into aligned holes in respective sections through causing right and left hand tension screws, of less pitch, to be screwed simultaneously into both sections for the purpose of drawing such sections together with greater power than resistance offered by the tie members whereby the sections are caused to move toward one another and screw the tie members into the respective sections until the contiguous edges of said sections are in abutting relation, thereafter removing the portions of the sections with which the tension members co-operate and thereafter shaping the resulting blank into the form of a finished seat.

In testimony whereof I have signed the foregoing specification.

WILLIAM F. TILE.
